UNITED STATES PATENT OFFICE.

EUGENE F. GOODMAN, OF NEW YORK, N. Y.

SHEET-FEEDING MACHINE.

SPECIFICATION forming part of Letters Patent No. 601,562, dated March 29, 1898.

Application filed April 9, 1897. Serial No. 631,446. (No model.)

To all whom it may concern:

Be it known that I, EUGENE F. GOODMAN, a citizen of the United States, residing at New York, in the county and State of New York, 5 have invented new and useful Improvements in Sheet Feeding or Gathering Machines, of which the following is a specification.

This invention relates to feeders by which sheets are fed successively from a pile to a ruling, folding, or other machine or to a printing-press; and the object of the invention is to construct a feeder which is simple and reliable in operation and which can be readily adjusted; and the invention resides in the 15 novel features of construction set forth in the following specification and claims and illustrated in the annexed drawings, in which—

Figure 1 is a plan view of a paper-feeder. Fig. 2 is a section along $u u$, Fig. 1. Fig. 3 20 is a section along $v v$, Fig. 1. Fig. 4 is a section along $w w$, Fig. 1. Fig. 5 is a section along $x x$, Fig. 1. Fig. 6 is a section along $y y$, Fig. 1. Fig. 7 is a section along $z z$, Fig. 1. Fig. 8 is a sectional view of mechanism 25 for operating the lifting-racks of the sheet-support.

The legs 1 support top pieces 2, from which rise the bearings 3 for a shaft 4, suitably rotated or actuated, as by power or by hand— 30 as, for example, by a crank 5, Fig. 1. The shaft 4 carries or actuates a cam 6, actuating those parts by which one sheet after the other is fed from pile 8, as follows: This cam 6, acting against rollers 76, Fig. 1, on a bar 77, 35 causes such bar to reciprocate longitudinally, or forward and backward. As seen in Fig. 3, this bar 77 has a slot engagement with feeder-actuating shaft 4, so that the bar can swing as well as reciprocate on such shaft.

40 At its forward part the bar 77 rests on or engages a cam 78, which causes the bar to swing or to rise and fall. Said bar 77 carries a stem 79, with a feeding-foot 80, which when faced or padded, as by rubber 81, will secure a suitable contact with the top sheet on pile 8. The high part of cam 78 having raised the bar 77 to lift foot 80 away from the sheet-pile and the cam 6 having drawn or moved the bar 77 back, the low part of cam 78 is brought to position for allowing bar 77 to drop its foot 80 on the pile, or, rather, onto the top sheet of the pile. The cam 6 then throws or slides bar 77

forward, and the top sheet is thereby slid off the pile 8 toward the feed-rollers 10 and pressure-rollers 11, so as to pass the front or leading edge of the sheet in between such rollers. 55

The stem 79 can be made adjustable on bar 77 to properly set the foot 80, and said bar 77 is shown with a stem 82 for the reception of one or more suitable weights 83, causing the foot 60 80 to properly take or press onto the top sheet. The bar 77 or its foot 80 may be considered a four-motion feed. The releasing or lifting cam 78 is actuated by shaft 84, suitably driven, as by pulley-and-belt connection 85, 86, and 65 87, Fig. 1, from shaft 4.

The pile of sheets 8 rests on a table or support 12, and the sheets can be readily alined or placed in proper position by causing an edge of the sheets to rest against a top or 70 frame piece 2, as seen in Fig. 1. Pins or pegs 88, driven or stuck into the sheet-board 12 at proper points, will tend to keep the sheets from derangement. The sheet support or board 12 has a cross-piece 13, Fig. 3, with 75 side pieces or braces 14, and said support is carried by upwardly-extending racks 15. Back pieces or risers 16, Fig. 3, on side pieces 2 can be made to brace or steady the racks 15 for holding them in mesh with gears 17. 80 The racks are gradually raised during the operation of sheet-feeding, so that as the sheet-pile 8 diminishes the support 12 will rise to bring the remaining sheets successively within reach of the feeder 80 to be fed 85 off one by one.

The rack 15 is engaged by gear-wheels 17, secured to tubular shaft 18, Figs. 1 and 8. The tubular shaft 18 is mounted on and can rotate independently of the shaft 19, having 90 its bearings 20 supported by the frame parts or lateral top pieces 2, Fig. 1.

Formed integral with the gear 17 is a head or disk 21, (see Fig. 8,) in which are fixed headed studs 22, which rest in apertures 95 formed in clutch-jaws 23, that are adapted to be clamped about a disk or head 25, rigid on the shaft 19, by screws or bolts 24.

The rotations of shaft 19 are communicated through the clutch arrangement 25 23 21 to 100 the sleeve 18 with gears 17, so that the latter will raise the rack 15 with sheet-support 12. If, however, the shaft 19 should be turned excessively or at improper moments, as when

the sheets 8 are already in position to be firmly pressed or gripped by feeder-face 81, the disk or head 25 will slip in the jaws 23, so that the sleeve 18 will not rotate and breakage is avoided.

The shaft 19 receives a step-by-step rotation as follows: Secured to shaft 19 is a transmission-gear or worm-wheel 26, engaged by worm 27 of shaft 28. This worm-shaft 28 has its bearings 29 on a top piece 2, Fig. 1. Secured to the worm-shaft is a ratchet 30, Fig. 2, engaged by pawl 31, carried by lever 32 33, loosely fulcrumed on shaft 28 and having its arm 32 overweighted, so that the arm 33 rests against lever 34, Fig. 3, fulcrumed at 35. The cam 36, secured to and rotating with feeder-shaft 4, oscillates the levers 34 and 33 32 with pawl 31, so as to intermittently rotate shaft 28 with gears 27 26 and shaft 19. A crank or handle 37, Fig. 3, enables the shaft 28 to be turned for rapidly adjusting or moving the support 12 to position for receiving a charge of sheets or for starting the feeding operation. The pawl 31, Fig. 2, when swung out of engagement with ratchet 30, leaves the shaft 28 free for retrograde movement by handle 37.

In order to prevent any but the top sheet being taken off the pile, the following arrangement is provided: A tube 90 is adjustably secured, as by screw 91, Fig. 1, to a rock-shaft 92, having its bearings 93 on a side piece 2, the free end of tube 90 being extended across the sheet-pile 8 to near the opposite side piece 2 or the sheet edges at said last-named side piece. This tube 90 is oscillated by rock-shaft 92 to carry the free end of tube 90 onto and away from the pile 8. The shaft 92 is rocked by arm 94, Fig. 3, which is actuated by spring 95, Fig. 1, to throw the free end of the tube 90 onto the sheet-pile. The cam 96 on shaft 4, acting against arm 94 to swing the latter against the tension of spring 95, will raise the free end of tube 90 off the sheet-pile. By forming the cam with a suitably-abrupt step from its high to its low part the spring 95 will be allowed to throw the free end of the tube onto the sheet-pile with certain abruptness or so that the free tube end 50 strikes the pile or the top sheet with a blow or snap. The tube 90 when suitably connected with a vacuum or exhaust mechanism will have a current of air flowing in at its mouth or at the free end of the tube, so that on the tube contacting its mouth or free end with the top sheet of the pile 8 such top sheet will be held or, as it might be popularly expressed, "sucked" to the tube-mouth, so as to adhere to and rise with the latter when the rock-shaft 92 swings up the suction-tube or lifter 90. The free end or mouth of this suction-tube, as seen in Figs. 5 and 7, is not formed or cut off square, but has an inclined edge or outwardly facing or opening bevel, so that as said free tube end snaps onto the top sheet the latter will have an edge or corner somewhat tilted or bent up from the underlying

sheet or pile, thereby allowing air to enter between the top and the underlying sheet, so that on the rise of the tube 90 with the top sheet adhering to the tube-mouth no underlying sheet will adhere to such top sheet and the edge of but one sheet will be raised at a time by the rise of tube 90. The sheet-board 12, as seen in Fig. 7, by having a depression 97 at or below the point where the tube-mouth strikes will insure the sheets of the pile, when the latter is about exhausted, being tilted up at an edge or corner by said remaining sheets being dented into the hollow 97 by the descending tube 90. Each top sheet is thus in turn suitably bent to be separated from the under sheet and to sit snugly against the suction-mouth or free end of the tube. A finger or stripper 98, Fig. 1, of curved or other suitable shape, causes the lifted sheet to be released or dropped from tube 90 after the latter has risen a certain distance. The stripper 98 is adjustably secured, as by slot-and-screw connection 99 and 100, so that the stripper as well as the suction-tube can be set for sheets of varying lengths.

A finger or detent 38 has a four-motion play. When the suction-tube is lifting the top sheet or an edge thereof off the pile 8, 95 said finger 38 is back of the rear edges of the pile to allow the rear edge of the top sheet to be raised by or to move up with the suction-tube. As the rear edge of the top sheet is lifted sufficiently high the finger 38 moves forward 100 beneath such raised sheet edge and above the underlying pile of sheets until said finger is over such underlying pile or over that portion of the pile which is near its rear edge. The finger 38 thus drops or presses onto such 105 pile to hold the latter, and the lifted sheet having been stripped off the tube 90 by stripper 98 will drop on top of detent 38, so as to be free for being fed off by feeder-face 81, while such detent holds down the underlying 110 pile to prevent all but such loose upper sheet from being taken by the feeder. After the top sheet is fed off the detent 38 rises to free the pile and then recedes back of the rear edge thereof to allow what is now the top 115 sheet to be raised in its turn by suction-tube 90. This four-motion play of detent 38 is effected as follows: The detent or finger 38 is adjustably secured, as by a screw 39, to a shaft 40, Fig. 1, which can rock and also move 120 longitudinally in its bearings 44. The rocking of the shaft 40 causes the free end of finger 38 to swing from and toward the top of the pile, and the longitudinal movement of the shaft carries the finger back and forward 125 of the rear edge line of the pile. The shaft 40 has an arm 46, which contacts or engages with a cam 51 on shaft 4 and which cam may be considered a double cam, having faces or being shaped to give arm 46 a reciprocating as also an oscillating motion. The reciprocating motion of the arm 46 produced by one face of cam 51, in connection with returning-spring 43, Fig. 1, will give the shaft

- 40 a reciprocating or longitudinal motion. The swing of the arm 46 produced by the other face or part of cam 51, in connection with returning-spring 101, Fig. 1, will rock the shaft 5 40 to raise and lower the free end of finger 38. By the tension of the spring 101 the finger 38 is held down at suitable moments on the underlying pile 8 to hold the latter against movement as the successive top sheets feed off.
- 10 The pile of sheets is prevented from rising above the proper level, or, if too high, depressed to the proper level, by a sheet-stop 102, Fig. 2, the stem 103 of which is guided by arm or bearing 104. A spring 105 tends 15 to lift the stop 102 off the sheet-pile, and at proper moments a cam 106 on shaft 4 acts against stop 102 or against a roller on said stop to depress the latter with the sheet-pile or to prevent the latter being raised too high.
- 20 The sheet-pile rests on the table 12, which is movably held by means of the friction-jaws 23, and in case said table, with the pile, should have risen too high the stop 102, descending or being pressed onto the pile by the cam 25 106, will push down the table 12 against the friction or hold of jaws 23 until said table is in position to hold the top sheet at the proper level.

The feed-rollers 10 have their shaft 60 30 driven by gears or connection 61, Fig. 1, driven by belt 62 and pulley 63 on shaft 4. The pressure-rollers 11 are journaled in arms 64, swinging loosely on shaft 65, and these arms 64, with rollers 11, are sufficiently heavy or weighty or 35 exposed to spring-pressure so that said rollers 11 bear with requisite pressure on the rollers 10 or on the sheet, which, being fed away from the pile, passes between said rollers 10 and 11. The shafts 60 and 65 are supported by arms 66, extending from frame 1 and 2.

The sheet support or board 12 can be stopped against excessive descent by flanges or stops 70 on frame parts 2.

45 The shaft 4 carries a pulley 71, Fig. 1, from which extends a belt or connection 72 to roller 73, which, with roller 74, supports a belt or carrier 75. As the sheets coming from rollers 10 and 11 are deposited on said carrier the latter can suitably transport the sheets to any required point for being gathered, as into books, or utilized as seen fit.

50 The detent 38, as noted, prevents the lower sheets or the sheets below the top sheet from moving forward with such top sheet as the latter is pushed or moved forward by the feeder.

In case the carrier 75 is used to gather sheets from several supports 12 said carrier 75 is extended or replaced by a longer carrier 60 and the rollers 73 74 are set farther apart, so that the carrier 75 will travel past the several supports, while if sheets are to be taken off from only one support 12 a shorter carrier 75, as shown in Fig. 1, will suffice.

65 The pusher or feeder 80 being properly timed will push or feed off the sheets one by one. The finger or detent 38 may have its contact

part padded, as with rubber, to secure efficient grip or pressure on the pile of sheets.

The pawl-lever 32 33, besides being over-weighted, may connect with a retraction-spring, as 89, Fig. 2.

The screws or pins 22, shown in Fig 1 as projecting from disk 21, serve to carry or support the jaws 23 on disk 21 in case these jaws 75 and the interposed disk 25 should be temporarily drawn apart or separated, as for repairs. The gear-wheel 17 and disk 21 are both secured or fixed to shaft 18, and said parts 17 and 21 can be practically cast or formed in 80 one piece. The clutch-jaws 23 being tightened or drawn together by the screws 24, said clutch-jaws and the disk 21 are secured together by the studs 22 on disk 21. The jaws being held or clasped against said studs by the 85 screws 24, the heads of the studs prevent the jaws from moving laterally or away from the disk. The jaws thus retain the position shown in Fig. 1, close to a side of the disk 21, as long as the jaws are clasped or held together by the screws 24.

What I claim as new, and desire to secure by Letters Patent, is—

1. A sheet holder or support, a sheet-feeder, and a sheet-detent, combined with mechanism substantially as described for actuating the feeder and detent, an actuating rack and gear for the holder, and a transmission-gear and cam-actuated worm-shaft for the holder-actuating gear, said transmission-gear and 95 holder-actuating gear being frictionally or slippingly connected to allow lost or slip motion for preventing excessive feed of the holder substantially as described.

2. A sheet holder or support, a sheet-feeder 105 and an intermittently-actuated sheet-detent, combined with an actuating rack and gear for the holder, a transmission-gear and worm-shaft for the holder-actuating gear, a ratchet and pawl for actuating the worm-shaft, and 110 an actuating-shaft for the feeder, said feeder-actuating-shaft being provided with a cam made to actuate said pawl and ratchet, said transmission-gear and holder-actuating gear being frictionally or slippingly connected to 115 allow lost or slip motion for preventing excessive feed of the holder substantially as described.

3. A sheet holder or support, a sheet-feeder, and an intermittently-actuated sheet-detent, 120 combined with an actuating-shaft for the feeder, an actuating-rack for the sheet-support, a gear made to engage the rack, a sleeve or tubular shaft for said gear, a shaft made to support or pass through and frictionally or 125 yieldingly connected to the tubular shaft, a driving gear or worm for the tube-supporting shaft, and a ratchet and pawl for actuating said worm, said feeder-actuating shaft being provided with an actuating-cam for said pawl 130 and ratchet substantially as described.

4. A sheet holder or support, a sheet-detent and suction-tube made to engage a rear corner portion of the sheets, cams for actuating

- the detent, and a rock-shaft for actuating the suction-tube, combined with a sheet-feeder made to engage the front or leading portion of the sheets, a supporting-bar for the feeder, a 5 movable cam made to engage the rear portion of the bar, for reciprocating the latter, and a lifting-cam made to engage the front portion of the bar, substantially as described.
5. A sheet holder or support, and a sheet-de-
tent, combined with a sheet-feeder and an os-
cillating suction-tube for lifting the sheets,

15 said tube having an inclined sheet-contacting mouth and said holder being recessed at the striking-point of said tube-mouth substantially as described.

In testimony whereof I have hereunto set my hand in the presence of two subscribing witnesses.

EUGENE F. GOODMAN.
